INFLATABLE BUOYANT BODY FOR MARINE USE

Knut Beyer-Olsen and Otto Steffensen,
Aalesund, Norway

Filed Sept. 19, 1969, Ser. No. 19,216

Claims priority, application Norway Mar. 24, 1969

Term of patent 14 years

Int. Cl. D12—14

U.S. Cl. D71—1

Fig. 1

Fig. 2

Fig. 3

FIG. 1 is a side view of the inflatable buoyant body having an apertured fastening member, showing the throughgoing opening for a rope or the like, and being the same in appearance when viewed from the opposite side,

FIG. 2 is a perspective view of the inflatable buoyant body shown in a smaller scale,

FIG. 3 is a plan view of the inflatable buoyant body.

We claim:

The ornamental design for an inflatable buoyant body for marine use, as shown and described.
